UNITED STATES PATENT OFFICE.

HENRY WILLIAM GREMMELS AND GEORGE SOMERVILLE, OF DENVER,
COLORADO.

POCKET BOOK OR CASE.

SPECIFICATION forming part of Letters Patent No. 642,323, dated January 30, 1900.

Application filed June 29, 1899. Serial No. 722,232. (No model.)

To all whom it may concern:

Be it known that we, HENRY WILLIAM GREMMELS and GEORGE SOMERVILLE, citizens of the United States, residing at Denver, 5 in the county of Arapahoe and State of Colorado, have invented certain new and useful Improvements in Pocket Books or Cases, of which the following is a full and complete specification, such as will enable those skilled 10 in the art to which it appertains to make and use the same.

This invention relates to pocket books or cases; and the object thereof is to provide an improved device of this class which is adapted 15 to be folded into a small compass and which is primarily designed for carrying money in the form of bills, but which may also be employed for carrying papers of any kind or class; and with this and other objects in view 20 the invention consists of the pocket book or case constructed as hereinafter described and claimed.

The invention is fully disclosed in the following specification, of which the accompanying drawings form a part, in which—

Figure 1 is an inside plan view of our improved pocket book or case extended or unrolled; Fig. 2, a longitudinal section on the line 2 2 of Fig. 1; Fig. 3, a view similar to Fig. 30 1, showing the pocket book or case folded up; Fig. 4, a section on the line 4 4 of Fig. 1; Fig. 5, a partial view, similar to Fig. 1, of a modified form of construction; Fig. 6, an end view thereof, and Fig. 7 a partial section on the line 7 7 of Fig. 5.

In the drawings forming part of this specification the separate parts of our improvements are designated by the same numerals of reference in each of the views, and in the 40 practice of our invention we provide a pocket book or case of the class described comprising a frame composed of two parallel side bars 10 and 10^a, connected at their opposite ends by oblong plates 11, having segmental 45 ends and with which are connected outside end plates 12 of similar form and slightly larger in longitudinal and transverse section, and between the plates 11 and 12, at each end, is a chamber 13, open at one side and 50 preferably formed by a flange 14, formed in the plate 12 and extending between the points 15

and 16 in Fig. 4, the top portion in said figure between said points being open, and pivoted in each of said chambers is an arm 17, the outer or free ends of which are connected 55 by a longitudinal bar 18.

The arms 17 are pivoted in the chambers 13, as shown at 19, and said arms are provided with heads through which the pivots 19 pass, said heads being flat on two 60 sides, and in each of the chambers 13 is secured a spring 20.

The springs 20 bear on the heads of the arms 17 and hold them either in an open or closed position, the open position being shown 65 in dotted lines in Fig. 4 and the closed position in full lines, and when said arms are in the closed position they fill up the open space in the flange 14 between the points 15 and 16, and each of the arms 17 is preferably provided in the back thereof with a notch or recess 21, which receives the end of the flange 14 when said arms are in the open position, as shown in said figure.

The arms 17 and the bar 18, by which the 75 free ends of said arms are connected, together with the springs 20, constitute a clamp for holding the bills or other articles in the pocket book or case, and secured to the frame between the outer end plates 12 is a sheet 22 80 of leather or other suitable flexible material, which is adapted to be wrapped around said frame, as shown in Fig. 3.

In securing the sheet 22 of leather or other flexible material to the frame it is wrapped 85 around the side bars 10 and 10^a and around the flanges 14, by which the chambers 13 are formed between the plates 11 and 12, and when the said sheet of flexible material is wrapped around said frame so as to close the 90 pocket book or case, as shown in Fig. 3, the entire frame is concealed, except the outer end plates 12.

The free end of the flexible strip 22 is provided with a strap 23, which is connected 95 therewith by an eyelet 24, provided at one end with a spring-head 25, and the strap 23 is provided at its free end with an eyelet 26, and said strap is wrapped around the pocket book or case, as shown in Fig. 3, and the eyelet 26 100 connected with the spring-head 25 of the eyelet 24, and the parts 25 and 26 are similar to

an ordinary glove-fastener and form a secure fastener for the pocket book or case.

The bar 18 of the spring-operated clamp and the part 10 of the frame, in connection with which the bar 18 operates or on which said bar 18 operates when the clamp is closed, are substantially the same in cross-section as the bar 10 at the opposite side of the frame, this construction of the parts being best 10 shown in Fig. 2, and in Figs. 1 and 2 we have shown at 27 a number of bills inserted between the side bar 10 of the frame and the bar 18. In order to do this, the clamp is thrown backwardly, as shown in dotted lines 15 in Fig. 2, and the bills placed in position, after which the clamp is thrown forward, as shown in full lines in said figure. Any desired number of bills may be thus placed in the pocket-book, and the leather may be 20 rolled up, as shown in Fig. 3, and conveniently carried in a pocket.

In Figs. 5 to 7 we have shown a modification in which the end plates at each end of the frame are of the same size in longitudinal 25 and transverse section and are designated by the reference-numerals 28 and 28^a, and between said end plates at each end is a chamber 29. In this form of construction a flange 30 is formed on the bottom portion of one of 30 said plates at each end of the frame and closes the bottom and front portions of the chamber 29, and arms 31 are pivoted in the rear ends of said chambers and provided with segmental heads 32, which close said chambers at said 35 ends, and the free ends of the arms 31 are connected by a cross-bar 33, similar to the bar 18 in Fig. 2, and in each of the chambers 29 is secured a spring 34, which serves to hold the arms 31 both in an open and closed position. 40 In this form of construction the plates 28 and 28^a at each end of the frame are provided in the upper corners thereof, opposite the pivotal supports of the arms 31, with notches or recesses 35, which receive a head formed on 45 the free ends of said arms, and one of said heads is provided with a downwardly-directed lug or projection 36, which is milled on its outer surface and which serves as means for raising the clamp consisting of the bar 33 and the arms 31. In this form of construction 50 horizontal side bars 37 and 38, similar to the bars 10 and 10^a, (shown in Fig. 2,) are also employed, and the bar 38 is set inside the flange 30, as shown in Fig. 7. In the form of 55 construction shown in Figs. 5 and 7 the flexible strip or sheet 22 is not shown, these figures being designed to show a modification of the ends of the frame and of the clamp; but it will be understood that in practice the flexible sheet or strip 22 is connected with the 60 frame and secured to the bars 37 and 38 in the same manner as shown in Fig. 2.

Having fully described our invention, we

claim as new and desire to secure by Letters Patent— 65

1. A pocket-book, comprising an oblong frame, an oblong spring-operated clamp having end arms pivoted in chambers in the ends of said frame, and a flexible strip secured to said frame and adapted to be wound thereon 70 over said clamp, substantially as shown and described.

2. A pocket-book consisting of an oblong frame, comprising parallel side bars and end portions, said end portions being provided 75 with chambers open at one side, a spring-operated clamp having arms pivoted in said chambers, and a bar operating in connection with one of the side bars of the frame to hold bills or other articles, and a flexible cover secured to the frame between the end portions and adapted to be wound around said frame and said clamp, substantially as shown and described.

3. A pocket-book, provided with end portions having chambers open at one side, a clamp comprising a bar having arms pivoted in said chambers and spring-operated, and a flexible cover or strip secured to the frame between the end portions and adapted to be 80 wound around the same and around said clamp, substantially as shown and described.

4. A pocket-book, comprising a frame composed of parallel side bars, and end portions having chambers open at one side, a clamp 95 comprising a horizontal bar provided with arms pivoted in said chambers, springs mounted in said chambers for operating said clamp, and a flexible cover or strip secured to the frame between the end portions and adapted 100 to be rolled thereon and to inclose said clamp, substantially as shown and described.

5. A pocket-book consisting of an oblong frame, comprising parallel side bars, and end portions consisting of inner and outer plates, 105 the outer plates being larger than the inner plates, said end portions being provided between said plates with chambers open at one side, and a clamp provided with arms pivoted in said chambers, and a bar adapted to operate in connection with one of the side bars of the frame, and a flexible cover or strip secured to the frame between the end portions and adapted to be wound on said frame and around said clamp, substantially as shown 110 and described.

In testimony that we claim the foregoing as our invention we have signed our names, in presence of the subscribing witnesses, this 22d day of June, 1899.

HENRY WILLIAM GREMMELS.
GEORGÉ SOMERVILLE.
